PEANUT BUTTER GRINDER

Robert L. Zimmerman, 19 Viola Road,
Longmeadow, Mass. 01106

Filed Nov. 26, 1971, Ser. No. 202,717

Term of patent 3½ years

Int. Cl. D15—08

U.S. Cl. D55—1 B

FIG. 1.

FIG. 2.

FIG. 3.

FIG. 4.

FIG. 1 is a perspective view of a peanut butter grinder showing my new design;

FIG. 2 is a side elevational view thereof;

FIG. 3 is a top plan view thereof; and

FIG. 4 is an end elevational view thereof as viewed from the left of FIG. 2.

I claim:

The ornamental design for a peanut butter grinder, as shown.
